UNITED STATES PATENT OFFICE

WILLIAM T. BAUMAN, OF CHICAGO, ILLINOIS, ASSIGNOR TO UNIVERSAL FORM CLAMP CO., OF CHICAGO, ILLINOIS, A CORPORATION OF ILLINOIS

HIGH-CHAIR FOR CONCRETE REINFORCING SYSTEMS

Application filed February 24, 1930. Serial No. 430,956.

The main objects of this invention are to provide an improved bar support and spacer for use in reenforcing systems of concrete construction work; and to provide an improved high-chair for reenforcing bars wherein sections of identical construction are secured together to form the complete support and spacer, thereby reducing its cost and facilitating its manufacture and assembly.

An illustrative embodiment of this invention is shown in the accompanying drawings, wherein:

Figure 1 is a perspective of an improved high-chair.

Fig. 2 is a side elevation of the same, showing a reenforcing bar and mold soffit in section.

Fig. 3 is a top plan of an improved high-chair.

The common types of bar supports and spacers heretofore in use generally included two or more separately formed members of different shapes which were welded or otherwise secured together. It was, therefore, necessary for the manufacturer to carry in stock a large supply of each part of the units.

In the construction herein shown, the improved high-chair comprises two sections of substantially identical size and shape which are rigidly secured together to form the complete structure. This obviates the necessity of carrying in stock a large number of parts of different shapes and greatly facilitates the assembly of the units.

The high-chair is preferably made of round wire of comparatively heavy gauge, which possesses the necessary rigidity and which may be bent to the desired shape.

The reenforcing system involves the use of reenforcing bars 1, only one of which is shown, disposed horizontally above a false-work 2, and supported by the improved high-chairs.

In the construction shown, the improved chair comprises a pair of substantially identical sections 3, which are rigidly secured together.

Each of the sections 3 comprises a wire which is bent to form a horizontal shelf 4,

and an upstanding arm 5, having their outer ends bent downwardly to form depending legs 6 and 7, respectively. The shelf 4, arm 5 and leg 7 of each section are preferably located in a single plane, from which the leg 6 diverges downwardly.

When the sections are assembled, they are arranged as shown in Fig. 1, with the shelves 4, arms 5 and legs 7 of both sections located in substantially a single vertical plane and the legs 6 diverging downwardly on respectively opposite sides of that plane. The shelves 4 are preferably spot welded together, as shown at 8, and together with the arms 5 they form a substantially U-shaped saddle for supporting the reenforcing bar. The legs 7 of the assembled unit preferably diverge downwardly from each other.

The high-chairs embodying these improvements are exceedingly simple in construction and operation, comparatively inexpensive to manufacture, and very rigid when set up.

I claim:

1. A bar support comprising a substantially U-shaped wire saddle having a horizontal base part and a pair of upstanding arms, the upper ends of said arms being bent downwardly to provide a pair of end legs, and a pair of intermediate legs on respectively opposite ends of said base part, said intermediate legs diverging downwardly on respectively opposite sides of the plane of said saddle.

2. A bar support comprising a substantially U-shaped wire saddle having a horizontal base part and a pair of upstanding arms, the upper ends of said arms being bent downwardly to provide a pair of end legs, said end legs and saddle being disposed in substantially a single plane, and a pair of intermediate legs on respectively opposite ends of said base part, said intermediate legs diverging downwardly on respectively opposite sides of the plane of said saddle.

3. A bar support comprising a substantially U-shaped wire saddle having a horizontal base part and a pair of upstanding arms, the upper ends of said arms being bent downwardly to provide a pair of end

legs, said end legs diverging downwardly from each other within the plane of said saddle, and a pair of intermediate legs on respectively opposite ends of said base part, **5** said intermediate legs being located on respectively opposite sides of the plane of said saddle and diverging downwardly therefrom.

10 4. A bar support comprising a pair of connected wire sections of substantially identical construction, each of said sections comprising an L-shaped portion having both of its ends bent downwardly to provide a pair of depending legs, the L-shaped portions of both sections being united to form a U-shaped saddle for supporting a reenforcing bar.

15 5. A bar support comprising a pair of connected wire sections of substantially identical construction, each of said sections comprising an L-shaped portion having both of **20** its ends bent downwardly to provide a pair of depending legs, the L-shaped portions of both sections being united at their bases to form a U-shaped saddle for supporting a reenforcing bar, one leg of each section being disposed in the plane of said saddle, the other leg of each section diverging downwardly from said plane.

Signed at Chicago this 19th day of February, 1930.
